1 Claim 10

ABSTRACT OF THE DISCLOSURE

The invention relates to a cosmetic and conditioner for skin and hair, prepared with active principles that are soluble in a mixture of distilled water and 70% sorbitol solution and are obtained from the botanic specie denominated *Polypodium Phyllitidis L.*, Polipodiacias family.

SUMMARY OF THE INVENTION

While observing in the Caribbean Islands and Central America, the natives using a concoction for hair washing as a beautifying means and for the prevention of hair falling out, we decided to consult references appearing in a treatise written by Doctors Roig and Mesa, entitled "Plantas Medicinales Cubanas, Cuban Medicinal Plants" pages 529-530. It led us to make a series of studies to determine the active principles in certain botanic plants, and to find a formula and technique for the evaluation and production of a hair lotion, pleasing in odor, and also usable as a brilliantine.

The analysis made of our lotion has uncovered the following ingredients: hormones as 17-ketosteroids 2.40%, hydroxy-hormones 1.10%, biotin 0.47%, pantothenic acid 0.11%. The hydroxy-steroids include testosterone. We have discovered in a botanic specie, active principles, which according to the revised literature, prevent the falling of the hair besides giving to it a delicate luster. In "Practical Pharmacy" by Remington, second edition translated into Spanish, referring to biotin, states on page 1042 that biotin deficiency produces dermatitis and loss of hair. On page 1052 it suggests the use of pantothenic acid in the mane, due to its effect on white hair and finally on page 1015 it states that the androgen hormones, stimulate hair growth. In addition, the references found in revised literature and copies of invention patents we have seen, that have been concerned with protecting methods, etc. of obtaining hormones from vegetable sources, refer only to what is known as beginning materials to facilitate means to obtain hormones by synthesis performed in laboratories. We have found these hormones produced by the botanic specie itself, namely *Polypodium Phyllitidis L.*, Polipodiacias family, which we extracted with a mixture of distilled water and 70% sorbitol solution by heating to 212° F. useful to produce the cosmetic and conditioner of the instant invention.

Prior methods of preparing concoctions have been known for many years and have been shown in previous revisions of the United States Pharmacopea, they were not recommended for immediate use because the products obtained were poorly preserved. Our method offers the originality of employing a vehicle or as vehicle, a mixture of sorbitol and distilled water with the two preservative agents, methyl para-hydroxybenzoate and propyl para-hydroxybenzoate dissolved in the sorbitol before mixing the distilled water therein. This technique avoids the starting of fermentation in the product.

The botanic specie *Polypodium Phyllitidis L.*, exists in Puerto Rico, Virgin Islands, Jamaica, Bahamas, Florida,

2

and from Mexico to Paraguay. The formula which we employ for the preparation of the lotion is the following:

5	Root of <i>Polypodium Phyllitidis L.</i>	gm	235.00
	Leaves of <i>Polypodium Phyllitidis L.</i>	gm	115.00
	Methyl para-hydroxybenzoate	gm	15.00
	Propyl para-hydroxybenzoate	gm	5.00
	70% sorbitol solution	1	0.875
	Distilled water	1	5.600
	Alcohol (Ethyl or Isopropyl)	1	4.025
	Essence Portugal	1	0.050

BRIEF DESCRIPTION OF THE DRAWINGS

In the drawings:

FIG. 1 shows a typical formulation in accordance with our invention; and

FIG. 2 shows a process in accordance with our invention.

DETAILED DESCRIPTION OF PREFERRED EMBODIMENTS

The product exemplified by the formula shown at 10 in FIG. 1 provides a product that oils and conditions skin.

As shown in FIG. 2, this formula can be produced by the following process:

1. Wash roots and leaves of the botanic specie with water, to eliminate impurities and dry them by exposure to sun heat. (Step 12)

2. Grind separately roots and leaves. (Step 14)

3. Dissolve in the para-hydroxybenzoates in the sorbitol, heating at 176° F. and while agitating this solution add the distilled water and heat the whole mixture to 212° F. Then add the roots and leaves which appear in the formula, maintaining the temperature at 212° F. for a few minutes after the drug is added. Cover the receiver containing the preparation and let it cool. Then filter it, repeating until the liquid comes out clear. Extract by expression the last portions of liquid remaining in the frame (drug) putting it through the filter also. (Step 16)

4. The liquids once reunited should be completed with 5.925 l. of distilled water, adding it without stopping the agitating of the alcohol and the essence. (Step 18)

5. The preparation should be kept in repose, in a closed receiver ten days. Thereafter extract by decantation all the clear liquid, filter it and bottle. (Step 20)

While we have described our invention with particular reference to the drawings, such is not to be considered as limiting its actual scope.

Having thus described this invention, what is asserted as new is:

1. A method for producing a product used as a cosmetic and conditioner for skin and hair comprising the steps of:

sun of drying water-washed *Polypodium Phyllitidis L.* roots and leaves,

grinding said roots and leaves,

dissolve in approximately 0.875 l. of approximately 70% sorbitol solution approximately 15.00 gm. of methyl para-hydroxybenzoate and approximately 5.00 gm. of propyl para-hydroxybenzoate to provide a first fluid,

heating the first fluid at approximately 176° F., adding approximately 5.600 l. of distilled water and

while agitating this second fluid heating it to 212° F., maintaining the temperature at 212° F. for a few minutes while adding approximately 235.00 gm. of the ground roots and approximately 115.00 gm. of the ground leaves to produce a third fluid,

70

filtering the third fluid after it is cooled in a covered container,
adding approximately 5.925 l. of distilled water, agitating and adding approximately 4.025 l. of alcohol and approximately 0.050 l. of essence of Portugal to produce a fourth fluid,
the fourth fluid is held in repose in a closed recipient for approximately ten days, and extracting by decantation all the clear liquid to provide the product.
